ADJUSTABLE TEMPLATE FOR BENT VALVE STEMS

Lloyd M. Littlefield, Chicopee Falls, Mass., assignor to A. Schrader's Son, Incorporated, Brooklyn, N. Y., a corporation of New York

Application September 29, 1932, Serial No. 635,331

6 Claims. (Cl. 33—75)

The present invention relates to an adjustable template for convertible tire valves and aims to provide a device for determining the bending tool settings required for bending a convertible valve 5 for replacement purposes.

Convertible tire valve stems are made in various standard lengths and are adapted to be provided with either a single or a double bend depending upon the type wheel upon which the tire 10 equipped with such valve stem is to be mounted. Where the valve stem is provided with a double bend, the bend nearest the base or foot portion is usually approximately a right angle, whereas the bend near the inflating end of the stem may 15 be of any angle up to 90° but is usually either 30° or 45°. The length of the arm or section of the valve stem between the two bends, as well as the length of the inflating end arm can be chosen to meet any particular requirements. Where tires 20 are supplied on cars as original equipment, of course, the valve stems will be bent either by the manufacture thereof or by the tire maker. If such tires are to be replaced in the field at service stations, the convertible valve with which a new 25 inner tube is fitted must be bent to desired shape, and for this purpose suitable valve bending tools are provided. With these valve bending tools there must be used a chart containing tables of 30 settings for the lengths and angles to be bent for the different types of wheels and sizes of tires, the use of which tables requires a degree of intelligence greater than is possessed by many 35 service station operatives.

According to my present invention I provide 35 a template or gauge device having adjustable means, which, upon being brought into engagement with the valve stem to be replaced, will instantaneously indicate the proper settings to be made on the bending tool for bending a convertible valve stem into proper shape. The invention also embodies other features of novelty 40 which will be better understood from the detailed description which follows, when considered in connection with the accompanying drawing showing an embodiment of my invention, and 45 wherein.

Figure 1 is a side elevation of a template or gauge.

Fig. 2 is a section taken substantially along 50 the plane of the broken line 2—2 of Fig. 1.

Fig. 3 is a side elevation partly broken away, showing the manner in which the template is to be used.

Fig. 4 is a section taken along the plane of the 55 line 4—4 of Fig. 1.

Fig. 5 is a section taken along the plane of the line 5—5' of Fig. 3.

The template or gauge consists of three associated members designated by the reference characters A, B and C, which may be formed from 60

sheet metal, celluloid or other suitable material which can be stamped or molded into proper form. As herein shown, the member A is in the form of an elongated, substantially flat element having a slot a extending longitudinally thereof and being formed at one end with a rearwardly directed flange or abutment a¹ and a cut-out portion a², and carrying on its front face beneath the slot a numerical indicia a³ arranged in four horizontal rows which are divided to provide a plurality of vertical columns, the tops of which terminate in central pointers a⁴. The numbers in the extreme left hand column represent four standard sizes of convertible valve stems and the numbers in the horizontal rows opposite each 15 of the aforementioned numbers in the vertical column represent points on a valve bending tool at which an adjustable abutment may be set to engage the valve inflating end of the valve stem to be bent and thereby govern the point on said 20 valve stem at which the bend between the inflating end arm and the intermediate arm of a double bent valve is to be made.

The member B is mounted to slide upon the member A and is provided with pins b which extend through the slot a for guiding said member in its sliding movements. To additionally guide said members and render the device more sturdy, a longitudinal flange b¹ which extends from the top edge of the member B for a greater 30 portion of its length, bears upon the top edge a⁵ of the member A. The flange b¹ terminates somewhat inwardly from the right hand end of the member B, as shown in the drawing, for a purpose which will be presently made apparent. 35 At the left hand end of the member B it is provided with a pointer b² for cooperation with the indicia a³, and to facilitate and render all of said indicia visible for all settings of the device, the lower left hand edge of the member B is cut away or chamfered off, as shown at b³. At its right hand end the face of the member B carries alphabetical indicia b⁴ arranged in concentric arcs for the purpose of compactness, said 40 indicia being for the purpose of indicating the setting on the valve bending tool of the angle of the bend to be formed in the convertible valve stem between the inflating end arm and the intermediate arm of a double bent valve stem.

The member C is pivotally mounted to the member B at the upper right hand corner thereof through the medium of a pivot pin c provided with suitable tensioning means for holding the parts in any adjusted position to which they may be set, and said member C at its end adjacent the pivotal mounting is provided with a pointer c¹ for cooperating with the indicia b⁴ for indicating the angle of bend to be made in the valve stem. At its upper longitudinal edge the member C is provided with a flange c² which termi- 55 60

nates in spaced relation to the pivotal axis of said member, and the latter on its front face is provided with a measuring scale c^3 for directly indicating the length of the inflating end arm 5 of the valve stem to be replaced.

In the use and operation of my template and gauge, the manner of duplicating a bent valve stem in the field from a convertible valve stem with which the inner tube is normally equipped, 10 is as follows:

Let us assume that the double bent valve stem D attached to an inner tube d which has been rendered useless is to be replaced at a service station in the field. The service station operative, in order to determine the length of the valve stem arms d' and d^2 , and the location of the point d^3 at which the bend is to be made in the valve stem, as well as the angle of said bend, applies the template to the valve stem by 15 having the flange or abutment a' engage against the flat side of the valve stem arm d' , the flange b' engage over the arm d' , and the flange c^2 engage over the arm d^2 , after which the member B is moved to the right until the end of the flange b' abuts against the valve stem within 20 the bight of the bend d^3 therein. The indicator b^2 will thereupon be found to point to one of the vertical columns of the indicia a^3 , and the particular number in said column in the horizontal row corresponding to the size of the valve 25 stem will indicate the setting on the valve tool necessary to produce a valve stem with arms equivalent to d' and d^2 . The indication of the pointer c' upon the alphabetical indicia b^4 informs the operative as to the setting to be 30 made on the bending tool for reproducing a bend in the valve stem corresponding to that in the one which is to be replaced. Thus in Fig. 3, the bending tool settings for duplicating a size 76 convertible valve stem are 13 and I; for a number 35 77 valve stem 18 and I and for a number 78 valve stem 26 and I. The indicia c^3 directly indicates the length of the arm d^2 of the valve stem. This latter reading, however, is not 40 so important, since the indicia a^3 indirectly determines this fact by indicating the size of valve stem to be used and the distance between the bend d^3 and the substantially right angular bend d^5 .

50. The device is exceedingly simple in construction, can be cheaply and accurately manufactured, and its manner of use can be quickly imparted to any unskilled operative in a service station, thereby obviating improper bending of 55 convertible valve stems in the field with the attendant annoyance and inconvenience resulting therefrom, not to mention the intrinsic loss due to rendering valueless valve stems which are 60 improperly bent at the hands of an inexperienced operative.

The invention, it is to be understood, is susceptible of modification and I therefore do not wish to be limited to the details of construction herein disclosed, as the same may be varied 65 within the range of mechanical skill without departing from the spirit of the invention.

What I claim is:

1. A device of the character described, comprising three relatively movable members for simultaneously engaging the three arms of a double bent tire valve stem, and cooperating means on two of said members for indicating the angularity of the bend nearer the inflating end of the stem and means for indicating the distance of 75 said bend from said end.

2. A device of the character described, comprising a pair of members which are slidably relatively to each other, and a third member which is pivotally connected to one of the other members, abutments on said members for engaging the arms of a double bent valve stem, cooperating means on said first two members for indicating the length of the intermediate arm of the valve stem, and cooperating means on the third member and one of the other two members for 10 indicating the angularity of the bend of the valve stem near the inflating end of the stem. 5

3. A device of the character described, comprising a pair of members which are slidable relatively to each other, and a third member which is pivotally connected to one of the first two members, abutments on said first mentioned members for engaging the end arms of a double bent valve stem, cooperating means on said first two members for indicating the length of 15 the intermediate arm of the valve stem, an abutment on the third member for engaging the inflating end arm of the valve stem, and cooperating means on the third member and one of the other members for indicating the angularity of 20 the bend of the valve stem near the inflating end of the stem. 25

4. A device of the character described, comprising a pair of members which are slidable relatively to each other, an abutment on one of 30 said members for engaging the foot portion end arm of a double bent valve stem, an abutment on the other member adapted to engage in the bight of the bend between the inflating end arm and the intermediate arm of the valve stem, and 35 cooperating means on said members for indicating the setting to be made on a valve bending tool for governing the point at which the bend in the valve stem between the inflating end arm and the intermediate arm is to be made. 40

5. A device of the character described, comprising a member having indicia thereon arranged in a plurality of rows, a second member mounted to slide in guided relation on the first member and having indicating means movable with relation to the indicia on the first member, means on said members for engaging the end arms of a double bent tire valve stem to bring the indicating means into cooperative relation with the indicia, a third member pivotally connected to the 50 second member and having means for engaging the inflating end arm of the valve stem while the engaging means on the first and second members are in engagement with said stem, and cooperating means on said second and third members for indicating the angularity of the bend in the valve stem between the inflating end arm and the intermediate arm. 55

6. A device of the character described, comprising a pair of members which are slidable relatively to each other, and a third member which is pivotally connected to one of the other two members, abutments on said members for engaging the arms of a double bent valve stem, cooperating means on said first two members for indicating the setting to be made on a tire valve bending tool and governing the length of the intermediate arm of the valve stem to be bent, and 60 cooperating means upon the third member and one of the other members for indicating the setting to be made on the aforementioned valve bending tool and governing the angularity of the bend of the valve stem nearer the inflating end of the stem. 65
